UNITED STATES PATENT OFFICE.

JOSEPH L. WRIGHT, OF CLEVELAND, OHIO, ASSIGNOR TO WESTERN ELECTRIC COMPANY, INCORPORATED, OF NEW YORK, N. Y., A CORPORATION OF NEW YORK.

SEMI-AUTOMATIC TELEPHONE-EXCHANGE SYSTEM.

1,383,588.

Specification of Letters Patent.

Patented July 5, 1921.

Application filed October 29, 1915. Serial No. 58,569.

To all whom it may concern:

Be it known that I, JOSEPH L. WRIGHT, a citizen of the United States, residing at Cleveland, in the county of Cuyahoga and 5 State of Ohio, have invented certain new and useful Improvements in Semi-Automatic Telephone-Exchange Systems, of which the following is a specification.

My invention relates to semi-automatic 10 telephone exchange systems. In systems of this class connections between subscribers' lines are effected by means of automatic switching mechanism.

In my invention certain switches are automatically controlled over the subscribers' 15 lines while others are controlled by operators located at the central office. The switches controlled by the operators are driven in a predetermined manner to contacts of trunks and to contacts of called lines.

The switches for effecting connection with the trunks are termed "trunk switches," while those effecting connection with the 20 called lines are termed "connector switches."

The trunk switches controlled by the operator are predeterminedly driven to pre-selected trunks, while the connector switches are predeterminedly driven to the called 25 lines.

The line of the calling subscriber is automatically extended to the operator's position by means of automatic selector switches initially controlled over the calling line. After 30 the line is thus extended the operator sets up the number of the called line on a key-board provided for that purpose and also operates keys for bringing into operation apparatus which automatically selects the trunk to be 35 used. The trunk switches are driven predeterminedly to the preselected trunk by means of impulses transmitted over the trunk over which the call originated.

The impulses for selecting the called line 40 are transmitted over a special trunk to the connector switch containing terminals of the called line. In selecting an idle trunk or connector to be used by the trunk switch the automatic switching mechanism determines the number of impulses to be transmitted to the trunk switch in accordance 45 with the number of the selected trunk.

Two-wire trunks are used between the trunk selector and connector switches as

the test contacts ordinarily associated with 55 the trunk switches are eliminated by the use of the small number of trunk selecting switches associated with the operator's position.

Means are provided for causing the release of the switches over the two-conductor 60 circuits and for maintaining a switch in a busy condition as long as another switch is in association therewith.

My invention is illustrated in the accompanying drawings, wherein:

Figure 1 shows a subscriber's line circuit and controlling apparatus at the central office.

Fig. 2 shows the primary selector and 70 trunk selector circuit.

Fig. 3 shows the connector switch circuit.

Fig. 4 shows the key-set control circuit.

Fig. 5 shows an operator's key-set switch circuit.

Fig. 6 shows the control apparatus associated with an operator's key-board.

Fig. 7 shows an operator's key-board and sending device.

Fig. 8 shows a control circuit and apparatus for selecting an idle connector switch.

Fig. 9 shows the arrangement of the various sheets.

Referring to Fig. 1, the subscriber's station at A is equipped with apparatus usual 85 in common battery systems. The line wires from the station terminate at the central office in a line relay 2 through the contacts of a cut-off relay 1. The line relays are divided into groups of ten for each one-hundred lines. The winding of each group relay is connected in common to the winding of ten line relays so that when any line relay of a group is energized the group relay associated therewith is also energized. The group relay serves to render the row test contacts in the primary switch selectable, while the line relay serves to make the individual test contact in the primary switch selectable.

The switch W is common to a group of one-hundred lines and serves to pick out an idle primary switch.

Referring to Fig. 2 the primary switch is shown at C. The spindle of the switch besides containing wipers which engage the individual contacts is also provided with a row wiper 64 for selecting the row or group

- contact of the calling lines. The switch C first rotates to pick out the group of calling lines and then steps vertically until the contact associated with the calling line is found.
- 5 The tip and sleeve conductors are separated by the condensers 43 and 44. The answering end of these conductors terminate in wipers of the primary switch C while the calling conductors extend to wipers in the 10 trunk selector switch D. Battery supply is furnished the calling subscriber through the windings of relay 23 and the retardation coil 26. Relay 21 is the starting relay and corresponds to the line relay 2 as it controls the action of the operator's key-set switch (Fig. 5). Relay 22 is the row test relay, while 24 is the individual test relay. Relay 25 is operated when the key-set switch picks out the primary trunk. Relay 28 is 15 the interrupter relay and operated when either the rotary or vertical magnets of the switch C are energized. The circuits of these magnets are normally completed through the back contacts of this relay and so, therefore, whenever it is operated the magnet circuits are broken. The action set up between the magnets and relay causes a vibrating effect which causes the former to 20 propel the switch C.
- 25 Referring to Fig. 3, relays 352 and 353 are repeating relays for the connector switch E. The operation of these relays in response to impulses from the operators' sending devices in turn controls the action of the 30 stepping magnets 362 and 364, thereby causing the switch E to first rotate in order to select a group containing the called line and then step vertically to pick out the individual contact in the group.
- 35 Battery-supply is furnished the called subscriber through the windings of relay 357 and retardation coil 358. Relay 355 is the ringing relay operated intermittently by the commutator I, while 366 is the busy test relay. Relay 351 is controlled from the primary trunk and is used for rendering the connector switch busy and also for restoring the same in case the called subscriber fails to answer.
- 40 Relay 390 is a slow acting relay of the usual type.
- 45 Referring to Fig. 4, switch Y corresponds to and performs the same functions as the switch W (Fig. 1) and serves to pick out an idle key-set switch.
- 50 Referring to Fig. 5, the key-set switch M is similar to and acts in the same manner as the primary switch C. 168 is the row wiper connected to its row test relay 153. 154 is the individual test relay, while relay 156 is the signal relay and operated in series with relay 25 (Fig. 2) when the primary trunk is selected. Relay 152 is the starting relay corresponding to relay 21 (Fig. 2). Relay 55 155 is controlled by the answering button

248 and when energized connects the operator's telephone set to the tip and sleeve conductors of the trunk.

Referring to Figs. 6, 7 and 8, an operator's keyboard, sending device and controlling 70 circuits are shown. The key-board consists of three rows of buttons, each row comprising ten buttons. The first two rows of buttons R and S are used in conjunction with the sending device for transmitting a pre-determined number of impulses to the connector switch. No. 1 button of each row is connected to the contact on the sending device operated by a cam 232. No. 2 button of each row is connected to the contact operated by cam 233. The corresponding buttons in each row are connected to similar contacts in the sending device. The contact controlled by cam 232 is closed just long enough to maintain relays 202, 203 and 256 75 (Fig. 6) energized, while one impulse is being transmitted by each of the commutators 242 and 243 of the sending device. If No. 10 button is depressed then these relays will be controlled by cam 241 so as to allow ten 80 impulses to be transmitted by each of the commutators 242 and 243. The contacts of commutator 243 are connected to normally open contacts of relay 202, while contacts of commutator 242 are connected to normally open contacts of relays 203 and 256. When these relays are operated the impulses 85 are directed over the tip and sleeve sides of the trunks for controlling the connector switches and trunk switches. The impulses 90 are transferred in groups to the tip and sleeve conductors in certain order for operating the switches by means of the shifting switch N.

95 The buttons in the rows R and S are of the usual locking and indicating type and so arranged that when one button of a certain row is depressed it will release the button formerly depressed. The buttons in the row V are of a non-locking type. When any one 100 of these buttons is depressed it will operate an associated trunk relay. These buttons are termed "group buttons" or "trunk buttons", and are used for associating an idle one of a group of connector switches with 105 the sending device. I have illustrated but two of these trunk relays, 200 and 201, but in reality there would be ten.

110 In order to select an idle connector switch in a group containing the line of the called subscriber the proper button in the row V is depressed, thereby operating its associated relay which causes the switch O (Fig. 8) to automatically select an idle connector switch 115 in the group. In case the connector switches are arranged in groups of ten the switch O 120 would contain terminals connected to control wires leading to the ten connector switches of the group. When an idle connector switch of the group is selected then 125 130

impulse control wires from the sending device are associated with the portion 310 of the switch O.

Relay 320 is operated when an idle connector is selected and serves to connect the ten impulse control wires from the segments of the sending device to contacts in the portion 310 of the switch O. This portion of the switch performs the same functions as 10 the buttons in the rows R and S, namely, to select and connect the proper impulse wire to the common conductor 211.

As each connector switch utilizes two contacts in the switch O then for the ten 15 switches in the group there will be twenty contacts in the switch O.

The ten impulse wires are connected in order to contacts in the portion 310 corresponding to the contacts in the portion 20 312 to which the resistance coils are shown connected.

I have shown but five of the ten impulse wires connected to contacts of relay 320 and but ten contacts in the switch O.

25 If the connector switch selected is No. 1 then No. 1 impulse control wire will be connected through the portion 310 of the switch and through the medium of the shifting switch N to the winding of relay 256. When 30 this relay is operated the impulses corresponding in number to the units digit of selected connector switch are transmitted over the sleeve conductor to the trunk switch D. The tens impulses corresponding to the tens 35 digit of the selected connector for operating the trunk switch are connected to the tip conductor extending to the trunk switch by means of relay 203. The impulses for operating the connector switch are determined 40 by the buttons depressed in the rows R and S and are transmitted over the trunk conductors selected by the switch O.

From the foregoing it will be noted that 45 the impulses for operating the connector switch are predetermined and directly under control of the operator. The impulses for operating the trunk switch are automatically predetermined by the trunk relay operated by one of the trunk buttons in the 50 row V and according to the position assumed by the switch O. The connector switch is first selected and impulses in number corresponding to the number of the connector switch are then transmitted directly to the 55 trunk switch causing it to effect connection with the selected connector switch.

After the impulses are transmitted the switch M (Fig. 5) is automatically restored and in readiness to be used for another call.

60 Referring in particular to Figs. 6 and 8, the switch O remains in association with the selected connector switch during two steps, or while the wipers engage two sets of contacts. The switch stops in one position after 65 having selected the connector switch, and is

then shifted to the second position or contact in order to allow the impulses to be transferred from the rotary to the vertical relay of the connector switch. Relay 305 is slow acting and will not fully restore during 70 the stepping of the switch as described. Relays 300 and 204 are placed in series when any one of the control relays 200, 201 et cetera are operated. Relay 204 is adjusted so as not to operate in series with the winding of relay 300 and the resistance coil 301. When however, this coil is short-circuited relay 204 will operate. Relay 300, however, is so adjusted that it will operate in series 75 with the winding of relay 204 and the resistance coil 301.

The primary switches, key-set switches, trunk switches and connector switches are of the type shown in Patent No. 977,536, December 6, 1910 to C. H. North. These 85 switches first rotate and bring their wipers in line with proper groups of contacts and then step vertically, causing the wipers to engage individual contacts in the row.

Other details of the circuit and apparatus 90 will be best understood in tracing a call from a calling to a called subscriber's line.

The subscriber at station A upon removing his receiver closes the circuit of the line relay 2 in series with the group relay 3. 95 This latter relay operating closes the circuit of relay 4 which in turn connects ground to one terminal of the relay 5 and also closes the circuit of the stepping magnet 7. The stepping magnet operating closes the circuit 100 of relay 6 which in turn opens the circuit of the magnet itself causing it to vibrate and step the switch W. This switch will continue to rotate until an idle primary switch such as shown in Fig. 2 is found. As soon 105 as such a switch is found, the relay 5 is placed in series with relay 21, (Fig. 2) by the following path: ground, contact of relay 4, 5, 18, W, 14, 21, 70, contact of relay 24 to battery B. The relay 5 operating opens the 110 circuit of the magnet 7 bringing the switch W to rest.

Relay 21 operating closes the circuit of the rotary stepping magnet 31 by the following path: battery B, 80, back contact of 115 relay 24, 71, contact of relay 28, back contact of relay 22, 31 to ground. The operation of magnet 31 causes the switch C to rotate until the wiper 64 reaches the busy row contact.

120 The wiper 64 is carried on the same spindle with the wipers 63 and 65, and while the switch is rotating the wiper 64 passes over contacts leading to the group relay 3. As there are ten of these group relays to each 125 one hundred lines it follows that the wiper 64 in rotating to its extreme position will pass over ten contacts.

There are ten sets of individual contacts arranged in vertical rows associated with 130

each row contact and which the wipers 63 and 65 respectively engage. It follows therefore that after the switch picks out the group in which a line is calling, it will afterward step vertically until the wipers engage the contacts of the calling line.

As soon as the row contact is found, the circuit of relay 22 is closed as follows: battery B, 80, back contact of relay 24, 71, 22, 10 64, 13, contact of relay 3, to ground. The relay 22 in operating disconnects the rotary magnet 31 and in its place connects the vertical magnet 30, thereby causing the switch to step vertically until the busy individual 15 test contact is found. As soon as such a contact is found the circuit of relay 24 is closed as follows: battery B, 24, 68, contacts of relay 22, 67, 11, contacts of relay 2 to ground through the contacts of relay 1. 20 Relay 24 operating opens the wire 71 and disconnects relay 22 which in falling back disconnects relay 24 from the wire 67 and connects it instead to wire 66, thereby placing relays 24 and 1 in series.

25 The operation of relay 1 disconnects the line relay 2 and the group relay 3. Relay 24 connects battery to the windings of relays 23 and 25 and the falling back of relay 22 connects ground to the coil 26, thereby supplying the calling subscriber with talking current.

Relay 21 remains energized until the primary switch finds the calling line and until the key-set switch finds the trunk. Relay 35 21, when first actuated, places battery on the wire 79 to relay 130 and also places battery to wire 62 which is connected to the individual test contact of the key-set switch (Fig. 5).

40 Relay 130 closes the circuit of the stepping magnet of the switch Y through the normally closed contacts of relays 131, 132. The magnet in operating closes the circuit of the interrupter relay 134, thereby causing the magnet to vibrate and the switch to rotate until an idle key-set switch is found. When such a switch is found, as shown in Fig. 5, relay 131 is placed in series with relay 152 by the following path: ground, contacts of relay 130, 131, 138, Y, 140, 152, 195, 196, 197 to battery B through the operator's jack 400. Relay 131 operating places battery on wire 136 to relay 132. As soon as this latter relay operates, ground is placed 45 on the wire 138, thereby shunting relay 131. This direct ground placed on wire 138 makes the wire 140 which is multiplied to other Y switches busy. The operating of relay 132 also places ground on the row wiper of the 50 key-set switch by the following path: ground, 139, Y, 141, to the row contact.

The operation of relay 152 connects ground to the rotary magnet 165 through the back contact of relay 163 causing the 55 switch M to rotate. This switch will ro-

tate until the busy row contact is found, whereupon the circuit of relay 153 will be closed as follows: battery B, contacts of relay 152, 176, 153, 171, 168, 141, 139, contacts of relay 132 to ground. The key-set switch M operates in the same manner as the primary switch C (Fig. 2). Relay 153 disconnects the rotary magnet 165 and connects in its place the vertical magnet 164, thereby causing the switch to step vertically until the busy individual test contact is found. The finding of this contact closes the circuit of relay 154 as follows: ground, 154, 172, 62, 80, contacts of relay 21 to battery B. Relay 154 disconnects relay 152, 70 thereby cutting off the vertical magnet and causing the key-set switch to rest on contacts leading to the calling primary trunk. Relay 152 becoming deenergized opens the circuit of relay 153 and this latter relay 75 in falling back places relays 156 and 25 in series by the following path: ground, back contact of relay 153, 175, back contact of relay 157, 102, contact of relay 155, 156, 193, 169, 59, 25 to battery B through the contact of relay 24. The operating of relay 25 (Fig. 2) disconnects relay 21 and also relay 5 (Fig. 1). The releasing of relay 5 frees the switch W allowing it to pick out other primary switches. Relay 80 156 operating places battery on wires 181 and 183 causing the lamps 234 and 244 to light.

85 As soon as relay 21 in Fig. 2 became disconnected battery was removed from the individual test contact of the key-set switch, thereby allowing relay 154 to fall back. Relay 21 also releases relay 130, thereby restoring relay 132 so as to allow the switch Y to be used by other trunks in picking out 90 key-set switches.

95 In the present instance I have provided ten primary switches as shown in Fig. 2 for each one hundred lines. Each group of ten primary switches is in turn provided with one Y switch for picking out idle key-set switches. The percentage and grouping of the trunks and lines can be varied to suit traffic conditions.

100 The wire 141 leading from the Y switch 115 to the row contacts of the key-set switch is not multiplied. The Y switch picks out an idle key-set switch and this places ground on the row contact of the selected switch and these row contacts are not multiplied. 110 This arrangement prevents interference between other Y switches and also between the key-set switches. In no case is ground placed on more than one row contact of any key-set switch at the same time.

115 In Fig. 1 the switch W is individual to one hundred lines and picks out a group of primary switches, and in this case the row contacts of a group of primary switches 120 are multiplied.

The lighting of the lamps 234 and 244 notifies the operator of a call, and she then presses button 248 operating relay 155. The operation of this relay connects her telephone set across the trunk wires, disconnects relay 156, thereby extinguishing the lamps 234 and 244. The disconnecting of relay 156 also opens the circuit of relay 25, (Fig. 2) which in falling back closes the tip and sleeve conductors of the trunk, allowing the operator to converse with the calling subscriber.

The operator after receiving the number from a calling subscriber depresses buttons in rows R and S corresponding to the tens and units digits. After depressing these buttons the operator depresses a button in the row V corresponding to the hundreds digits of the called subscriber. In the present instance we will assume that the first button is depressed; the depressing of this button completes the circuit of relay 200. The operation of this relay connects the winding of relay 204 and the winding of relay 300 (Fig. 8) in series with the resistance coil 301. Relay 200 remains locked to ground through the back contacts of relay 206 and the button 208. Relay 300 becomes energized but relay 204 is not operated due to the high resistance of coil 301. The operation of relay 300 completes the circuit of the stepping magnet 304 of the switch O by the following path: ground, contacts of relay 300, contacts of relay 302, winding of magnet 304 to battery B. The operation of the magnet completes the circuit of the interrupter relay 302 by the following path: ground, contacts of relay 300, 314, contacts of relay 305, 315, 316, winding of relay 302, to battery B. The operation of relay 302 opens the circuit of the magnet 304 and the magnet in restoring again allows relay 302 to drop back. This action between the magnet and relay 302 causes the switch O to rotate until an idle switch is selected. As soon as such a switch is selected, such as shown in Fig. 3, then relays 303 and 350 are placed in series by the following path: battery B, contacts of relay 300, 326, winding of relay 303, 325, 312, 324, winding of relay 350, contacts of relay 490, 377, cam springs 370 to ground. The operation of relay 303 completes the circuit of relay 305. This latter relay in operating connects battery directly between the winding of relay 303 and the testing switch wiper 312, thereby rendering the contact upon which the wiper rests busy against other calls. The effect of battery being connected in this manner shunts relay 303 causing it to restore, but relay 305 remains locked to ground through the contacts of relay 300.

The operation of relay 305 also connects ground between the winding of relay 300 and the coil 301, thereby shunting out the re-

sistance. The shunting out of this resistance allows relay 204 (Fig. 6) to become energized. The operation of this relay then causes the lamp 207 to light, notifying the operator that an idle switch has been selected.

The operation of relay 204 completes the circuit of relay 157. The operation of this latter relay disconnects ground from the locking contacts of relay 155 and connects ground to the wiper 169, thereby operating relay 25, Fig. 2. The operation of this relay 25 severs the tip and sleeve conductors and also causes the operation of relay 42. The operation of this latter relay connects the relays 27 and 528 respectively to the conductors 54 and 53.

The operation of relay 204 after an idle switch is selected, also completes the circuit of the stepping magnet 205 of the switch N so that it can be operated by the springs controlled by the cam 231 of the sending device. As soon as the contact springs controlled by this cam are operated then the magnet 205 is operated and after the contacts are broken the switch wipers 250, 251 and 252 leave the first set of contacts and engage the second set. It will be noted that the winding of relay 204 is connected to battery through normally closed contacts of the magnet 205 and to battery through the contact upon which the switch wiper 252 normally rests. After the switch takes the first step then battery connection to the relay 204 is controlled wholly through the contacts of the magnet 205.

After taking the first step the common wire 258 of the row buttons R is connected directly to the winding of relay 202 through the switch wiper 250 and the common wire 401 of the trunk relays is connected directly to the winding of relay 203 through the wiper 251. Relays 202 and 203 are maintained energized for a certain length of time, depending upon the button depressed in the row and according to the trunk relay 100 operated.

The connector switch E is operated by means of impulses from the commutator 243 while the trunk switch D is operated by means of impulses transmitted by the commutator 242.

After the wipers of the switch N engage the second set of contacts relay 202 is maintained energized for length of time depending upon which button is depressed in the row R. Relay 203 is likewise held energized for length of time depending upon which button was depressed in the row V. The operation of one of these buttons operates its corresponding trunk relay which we will assume to be relay 200. The impulses from the commutator 243 are transmitted to the rotary relay 352 of the switch E by the following path: Ground, commutator 243, 262, contacts of relay 202, 263, contacts of relay 130

200, 212, 311, 323, winding of relay 352 to battery B. The operation of this relay, according to the button depressed in the row R, causes a corresponding operation of the 5 rotary magnet 362 by the following path: ground, contacts of relay 366, contacts of relay 352, 374, cam springs 371, 375, winding of magnet 362 to battery B. The operation of this magnet causes the switch E to 10 rotate to the proper position.

Impulses from the commutator 242 cause the operation of the rotary relay 27, of the trunk switch D by the following path: ground, commutator 242, 260, contacts of 15 relay 203, 261, 562, wiper 167, 61, 54, contacts of relay 42, winding of relay 27 to battery B. The operation of magnet 48 in response to the operation of relay 27 causes the switch D to assume a position with its 20 wipers in line with a row of contacts leading to the preselected connector switch.

The relay 203 for regulating the number of impulses to be transmitted has its circuit completed by the following path: ground, 25 contacts controlled by segment 232, 400, contacts of relay 200, 401, second contact in the portion 251 of the switch N, 265, winding of relay 203 to battery B.

After the termination of this first group 30 of two sets of impulses the circuit of the magnet 205 of the switch N has its circuit completed by the springs controlled by the cam 231 on the sending device. While the magnet circuit is closed the circuit of relay 35 204 is broken as battery is disconnected from its winding by the operation of the contacts of magnet 205. The opening of this relay circuit causes its deenergization as well as the deenergization of relay 300 with which 40 it is in series. Relay 204 restoring causes the signal lamp 207 to be momentarily extinguished. Relay 300 in restoring removes ground from the winding of the magnet 304 thereby causing the wipers of the switch O 45 to take one step and engage the second set of contacts associated with the selected connector switch. In taking this step relay 352 is disconnected from the trunk conductor 212 and relay 353 connected in its 50 place.

As soon as the impulse transmitted to the magnet 205 by the cam 231 has been delivered the magnet restores and causes the wipers of the switch N to engage the third 55 set of contacts thereby connecting the common conductor 257 of the row of buttons S to the winding of relay 202. The switch in assuming this position also connects an impulse control wire from one of the segments of the sending machine (which we will assume to be the conductor connected to the segments 237) to the winding of relay 60 256 by the following path: ground, contacts controlled by the segment 237, 402, contacts 65 of relay 320, contact of portion 310 of the

switch O, 211, contacts of relay 200, 403, portion 251 of the switch N, 404, winding of relay 256 to battery B.

The momentary restoration of relay 300 does not release relay 305, as it is made slow 70 acting for this purpose. The wiper 312 moving from the contact which is directly connected to the winding of 350 still maintains that relay energized as the next contact in the switch is connected to a contact 75 of relay 350 which engages a coöperating contact leading to the winding of the relay itself. With this method of control the relay 350 is initially energized over the first test contact associated with a connector 80 switch and is thereafter controlled over the second contact. The operation of relay 305 maintains direct battery connected to the wiper while engaging either of these two contacts thereby preventing the selection of that trunk by another switch O, the operation of relay 305 preventing the 85 operation of the interrupter relay 302.

After the switch N engages the third set 90 of contacts relay 202 is maintained energized for a length of time depending upon the button depressed in the row S. Relay 256 is likewise maintained energized for a length of time depending upon the segment 95 of the sending device selected by the switch O. The relay 202 while energized causes impulses to be transmitted to the vertical relay 353 of the switch E. The operation of this relay causes a corresponding operation of the vertical magnet 364 thereby causing the switch E to step vertically and its wipers engage contacts of the called line. While relay 256 is energized impulses are transmitted over the sleeve conductor through the switch wiper 167 of the switch M to the vertical relay 528 of the switch D. The number of impulses transmitted to the relay 528 will correspond to the position assumed by the switch O in selecting the switch E. The impulses are repeated by the relay 528 to the magnet 49 thereby causing the switch D to engage contacts leading directly to the preselected switch E. 100 105 110 115

After this last group of impulses have been transmitted to the switches D and E 115 the circuit of the stepping magnet 205 of the switch N is again completed by means of an impulse transmitted by the cam 231. After this impulse has been delivered the wipers of the switch N step to their fourth 120 or normal position. In moving to this position the wiper 252 sweeps over the contact 270 thereby momentarily energizing relay 206. The operation of this relay removes ground from the locking contact of relay 200 thereby disconnecting the sending device from the switch E and also completes the circuit of release magnet 166 causing the restoration of switch M. The restoration of relay 200 severs the connection between 125 130

relays 204 and 300. The latter relay in restoring removes ground from the locking contact of relay 305 and after a short time interval this relay restores and places the 5 switch O in condition to be used in extending other calls. The restoration of relay 305 removes battery from the test wiper 312 and the restoration of relay 300 removes battery from the winding of relay 10 303 thereby opening the circuit of relay 350. This relay in restoring opens the circuit of the slow acting relay 390. Before relay 390 restores ground is connected to the winding of relay 352 by the following path: ground, contacts of relay 350, 15 contacts of relay 390, winding of relay 352 to battery B. The operation of relay 352 at this time while the switch wipers are resting on contacts of the called line connects the test relay 366 to the test wiper 20 373. In case the called-for line is busy the relay 366 will become energized and connect ground directly to the winding of the release magnet 391 thereby causing the restoration 25 of the switch E. The operation of relay 366 also connects a suitable busy tone signal to one of the trunk conductors notifying the calling subscriber that the called-for line is busy. In case the called-for line 30 is not busy, then relay 366 is not affected and the connection remains extended to the called line.

Relay 356 is placed in series with the cut-off relay of the called line through the test 35 wiper 373. The operation of the cut-off relay disconnects the line relay and the operation of relay 356 completes the circuit of the ringing relay 355 by the following path: battery B, contacts of relay 356, 399, contacts of relay 359, winding of relay 355, commutator I to ground. The operation of relay 355 severs the tip and sleeve conductors and connects generator G to the called line. When the called subscriber removes his receiver tip relay 357 is operated thereby completing the circuit of relay 359.

After the called subscriber replaces his receiver relay 357 restores and completes the circuit of the release magnet 391 by the following path: ground, contacts of relay 357, 40 383, contacts of relay 359, winding of magnet 391 to battery B. The operation of this magnet causes the restoration of the switch and when the switch is fully restored cam springs 370 are operated thereby disconnecting ground from the locking contact of relay 359 causing it to restore to its normal position.

The calling subscriber replacing his receiver causes the deenergization of relay 23. This relay restoring completes the circuit of the release magnet 32 by the following path: battery B, contacts of relay 25, 76, contacts of relay 21, 75, cam springs 39, 74, 65 contacts of relay 23, 73, winding of the mag-

net 32 to ground. The operation of this magnet causes the restoration of the switch C and when the switch is fully restored cam springs 39 are separated and break the circuit of the release magnet 32. While the release magnet is energized ground is connected directly to the tip conductor 54 by the operation of the contacts associated with the magnet. This ground connection causes the operation of relay 351 associated with the connector switch (Fig. 3). The operation of this relay causes the deenergization of relay 490 so as to render the connector switch available or selectable for the other calls.

Relay 490 was operated at the first impulse received by the relay 352 from the sending device. The operation of this relay disconnects the winding of relay 350 from the cam springs 370. As long as relay 490 is operated the switch E cannot be again selected by the switch O. Relay 490 will remain energized until the calling subscriber causes the release of the switch C as just described.

The restoration of the switch C completes the circuit of the release magnet 554 of the switch D by the following path: ground, cam springs 57 of the switch D to battery B. The operation of magnet 554 causes the restoration of the switch D and when it has 95 fully restored the cam springs 57 separate and open the circuit of magnet 554.

In case the called-for subscriber does not answer then the calling subscriber replacing his receiver causes the release of the switches 100 C and D in the manner described and also causes the operation of relay 351. The operation of relay 351 besides unlocking relay 490 completes the circuit of relay 359 by the following path: ground, contacts of relay 357, contacts of relay 351, 379, winding of relay 359 to battery B. The operation of relay 359 completes the circuit of the release magnet 391 by the following path: ground, contacts of relay 357, 383, contacts of relay 359, 380, winding of magnet 391 to battery B. The operation of this magnet causes the restoration of the switch E, which upon 110 fully restoring operates the cam springs 370 and causes the restoration of relay 359. 115

It will be noted that the called subscriber retains control of the release of the switch E as long as the tip relay 357 is energized and the only effect of the operation of relay 351 under these conditions will result in the 120 restoration of relay 490 to partially complete the circuit over which the switch E may be selected by the switch O. When the called subscriber replaces his receiver and causes the release of the switch E then the 125 circuit over which the switch is selected will be completed through the cam springs 370.

The switch E cannot be selected after once being operated unless it has fully restored and the relay 490 also restored when the call- 130

ing subscriber causes the release of the switch C.

I have illustrated and described a system employing a plurality of trunk switches D and a plurality of connector switches E, each operator being provided with two rows of buttons for controlling the operation of the connector switches and a row of trunk buttons for causing the selection of a particular connector in a group, the selection of which automatically determines the number of impulses to be transmitted to the trunk switches D.

Having thus described my invention what I desire to secure by Letters Patent is:

1. In a telephone exchange system comprising subscribers' lines, talking trunks, automatic switches for uniting said lines and talking trunks into conversational circuits, a control trunk, separate trunks, means whereby a calling subscriber may communicate his order to an operator over said control trunk, means whereby an operator may directly control the operation of certain of said switches over a trunk separate from said control trunk, and additional means for controlling other of said switches over said control trunk.

2. In a telephone exchange system comprising subscribers' lines, talking trunks, automatic switches for uniting said lines and talking trunks into conversational circuits, a control trunk, separate trunks, means whereby a calling subscriber may communicate his order to an operator over said control trunk, means whereby an operator may directly control the operation of certain of said switches over a trunk separate from said control trunk, and additional means for controlling other of said switches over said control trunk, releasing means for said control trunk, said releasing means rendered operable after the operation of said switches.

3. In a telephone exchange system comprising calling and called subscribers' lines, a primary trunk, means for causing said primary trunk to be automatically connected with a calling line upon initiation of a call, a trunk switch permanently associated with said primary trunk, a connector switch for connecting with the called subscribers' lines, an operator's position and order trunk leading thereto, circuits separate from said order trunk, an electrically controlled selector switch at the exchange, means for initiating travel thereof to connect said primary trunk and order trunk in response to the operation of said selector switch, operators' means for transmitting directive currents over a circuit separate from said order trunk to said connector switch to establish a connection to the called line, additional means for directly operating said trunk switch to extend the connection from the calling line to said connector switch.

4. In a telephone exchange system, calling and called subscribers' lines, terminals therefor at the exchange, a primary trunk comprising a primary switch and a trunk switch, means for causing said primary switch to be automatically connected with a calling line upon the initiation of a call, connector switches for effecting connection with terminals of a called line, an operator's position and order trunk leading thereto, circuits separate from said order trunks, operators' means for transmitting directive currents over a circuit separate from said order trunk to establish a connection between the connector switches and the called line, additional operator's means for transmitting directive currents over said order trunk to establish a connection from the trunk switches to said connector switches.

5. In a telephone exchange system including a calling and a called subscriber's line, terminals therefor at the exchange, a link circuit comprising a primary switch and a trunk switch, said primary switch adapted to be automatically connected with a calling line upon the initiation of a call, a connector switch for effecting connection with a called line, an operator's position and order trunk leading thereto, separate circuits, operators' means for transmitting directive currents over a circuit separate from said order trunk to cause said connector switch to effect connection with the called line, means initially controlled by the operator for selecting said connector switch, additional means controlled by the selection of said connector switch for predeterminedly driving said trunk switch to effect connection with said connector switch.

6. In a telephone exchange system comprising calling and called subscribers' lines, a link circuit, means for causing said link circuit to be automatically associated with a calling line upon the initiation of a call, connector switches for effecting connection with the called lines, a trunk switch permanently associated with said link circuit for effecting connection with said connector switches, an operator's position and an order trunk leading thereto, circuits separate from said order trunk, means for automatically extending the link circuit to said position, means controlled at said position for selecting an idle connector switch over a circuit separate from said order trunk, means associated with said position for directly driving the selected connector switch to a called line, means controlled in the selection of the idle connector switch for directly driving the said trunk switch to the preselected connector switch.

7. In a telephone exchange system comprising calling and called subscribers' lines, a link circuit, means for causing said link circuit to be automatically associated with a calling line upon the initiation of a call,

- connector switches for effecting connection with the called lines, a trunk switch permanently associated with said link circuit for effecting connection with said connector switches, an operator's position and an order trunk leading thereto, circuits separate from said order trunk, means for automatically extending the link circuit to said position, means controlled at said position for selecting an idle connector switch over a circuit separate from said order trunk, means associated with said position for directively driving the selected connector switch to a called line, means controlled in the selection of the idle connector switch for directively driving said trunk switch to the preselected connector switch, said connector switch and said trunk switch being driven simultaneously to effect said connections.

20. 8. In a telephone exchange system comprising calling and called subscribers' lines, a link circuit, means for causing said link circuit to be automatically connected with a calling line upon the initiation of a call, a trunk switch permanently associated with said link circuit, connector switches for effecting connections with the called lines, an operator's position, means for associating said position with said link circuit, means controlled at said position for automatically selecting an idle connector switch, means at said position for causing said idle connector switch to effect connection with a called line, means controlled in the selection of said connector switch for causing said trunk switch to effect connection with the selected connector switch.

9. In a telephone exchange system, comprising calling and called subscribers' lines, a primary link circuit, means for causing said primary link circuit to be connected with a calling line, a trunk switch permanently associated with said link circuit, connector switches for effecting connection with the called lines, an operator's position, an order circuit extending from said link circuit to said position over which the order of the calling subscriber is taken, means associated with said position for selecting an idle connector switch, means controlled in the selection of the idle connector switch for causing said trunk switch to effect connection with the selected connector switch, additional means at said position for causing the selected connector switch to effect connection with a called line.

10. 10. In a telephone exchange system comprising calling and called subscribers' lines, a primary link circuit, means for causing said primary link circuit to be connected with a calling line, a trunk switch permanently associated with said link circuit, connector switches for effecting connection with the called lines, an operator's position, an order trunk extending from said link circuit to said position over which the order of a calling subscriber is taken, impulse controlling means at said position, a distributing switch controlled at said position for automatically selecting an idle connector switch, said distributing switch being provided with a plurality of contacts, means controlled through said contacts for connecting said impulse controlling means to

said order trunk for causing said trunk switch to select the idle or selected connector switch, and means at said position for connecting said impulse controlling means to the selected connector switch for causing it to effect connection with a called line.

13. In a telephone exchange system comprising calling and called subscribers' lines, a link circuit, means for causing said link circuit to be connected with a calling line, a trunk switch associated with said link circuit, connector switches for effecting connection with the called lines, an operators' position provided with an impulse sending device for controlling the operation of said switches, a distributing switch at said position provided with a plurality of contacts, means controlled over certain of said contacts for selecting an idle one of said connector switches, means controlled through other contacts of said distributing switch for connecting said impulse device to said trunk switch for causing it to effect connection with the selected connector switch, and means controlled at said position for connecting said impulse device to the selected connector switch for causing it to effect connection with a called line.

14. In a telephone exchange system comprising calling and called subscribers' lines, a link circuit, means for causing said link circuit to be connected to a calling line, a trunk switch associated with said link circuit, a plurality of groups of connector switches for effecting connection with the called lines, an operator's position provided with an impulse sending device, means at said position for selecting a particular group of said connector switches, and additional means for automatically selecting an idle connector switch in the group, means controlled in selecting an idle connector switch for connecting said impulse device to said trunk switch for causing it to effect connection with the selected connector switch, additional means associated with said position for connecting said impulse device to the selected connector switch to cause it to effect connection with a called line.

15. In a telephone exchange system including a calling and a called subscriber's line, a link circuit, means for causing said link circuit to be connected with the calling line, a trunk switch permanently associated with said link circuit, a plurality of connector switches for effecting connection with the called line, an operator's position, means associated with said position separate from said trunk switch for automatically selecting an idle one of said connector switches, additional means associated with said position for operating the selected connector switch to cause it to effect connection with the called line, releasing means for said connector switch, and additional means associ-

ated with said position for causing the trunk switch to effect connection with the idle connector switch after its selection, and means controlled over said trunk switch for actuating the releasing means of said connector switch.

16. In a telephone exchange system including a calling and a called subscriber's line, a plurality of connector switches, means for causing said switches to effect connection with the called line, releasing means for said switches, a trunk switch for effecting connection with said connectors, means separate from said trunk switch for selecting an idle one of said connector switches, and means controlled over said trunk switch for thereafter actuating the releasing means of said selected connector switch.

17. In a telephone exchange system, the combination with a called line, a plurality of connector switches for effecting connection therewith, a trunk switch for effecting connection with said connector switches, means separate from said trunk switch for selecting an idle one of said connector switches, and means controlled by said connector switch in effecting connection with the called line to render said switch unselectable, means controlled by said trunk switch for again rendering said connector switch selectable.

18. In a telephone exchange system, the combination with a called subscriber's line, of a plurality of connector switches for effecting connection therewith, means for selecting an idle one of said connector switches, a trunk switch, means for causing said trunk switch to be associated with the idle connector switch after its selection, means controlled in the operation of the selected connector switch in effecting connection with the called line for rendering it unselectable, means controlled over said trunk switch for thereafter rendering said connector switch selectable.

19. In a telephone exchange system, including a calling and a called subscriber's line, a plurality of connector switches, means for causing said switches to effect connection with the called line, a trunk switch, means for selecting an idle connector switch, means controlled in the selection of said connector switch for causing said trunk switch to effect connection therewith, means for causing the connector switch to effect connection with the called line, means controlled in effecting connection with the called line to render said connector switch unselectable, means controlled by the calling subscriber through said trunk switch for rendering said connector switch again selectable.

20. In a telephone exchange system comprising calling and called subscribers' lines, a link circuit, means for causing said link circuit to be associated with the calling line,

- a trunk switch permanently associated with said link circuit, a plurality of connector switches for effecting connection with the called line, an operator's position, means controlled from said position for automatically selecting an idle one of said connector switches, means thereafter controlled from said position for causing the connector switch to effect connection with the called line and the trunk switch to effect connection with the selected connector switch, means controlled in the operation of the connector switch in selecting the called line to render it unselectable, means controlled by the calling subscriber through the trunk switch for rendering said connector switch selectable. 5
21. In a telephone exchange system, the combination with a connector switch, of a trunk switch for effecting connection therewith, means independent of said trunk switch for selecting said connector switch, means for operating said connector switch when so selected to render it unselectable, and means controlled by said trunk switch 20 for again rendering said connector switch selectable by said independent means.
22. In a telephone exchange system, the combination with a plurality of connector switches, of a trunk switch, an operator's position, means controlled from said position for selecting an idle one of said connector switches, means thereafter for operating the selected connector switch and for operating the trunk switch to cause it to become associated with the selected connector switch, means controlled in the operation of the connector switch to render it unselectable, and means controlled by said trunk switch for again rendering said connector switch selectable. 30
23. In a telephone exchange system, the combination with a calling and a called subscriber's line, of a link circuit, means for causing said link circuit to be associated with the calling line, a trunk switch associated with said link circuit, a plurality of connector switches for effecting connection with the called line, means for preselecting an idle one of said connector switches independent of said trunk switch, and means for associating the trunk switch with the preselected connector switch. 40
24. In a telephone exchange system, the combination with a connector switch and a control relay therefor, of a trunk switch for effecting connection with said connector switch, means independent of said trunk switch for selecting said connector switch, means for operating said connector switch when selected to render it unselectable, means controlled by said trunk switch for operating said relay to render said connector switch again selectable. 50
25. In a telephone exchange system, the combination of a plurality of connector switches, a trunk switch for effecting connection with said connector switches, means separate from said trunk switch for selecting an idle one of said connector switches, and means controlled by the connector switch in its operation to render said connector switch unselectable, and means controlled by said trunk switch for again rendering said connector switch selectable. 70
26. In a telephone exchange system, the combination of a connector switch, a trunk switch for effecting connection with said connector switch, means separate from said trunk switch for selecting said connector switch, means controlled by said connector switch in its operation to render said switch unselectable, means controlled by said trunk switch for again rendering said connector switch selectable. 75
27. In a telephone exchange system, the combination of a connector switch, means for selecting said connector switch, a trunk switch, means for causing said trunk switch to be associated with said connector switch after its selection, means controlled in the operation of the connector switch for rendering said connector switch unselectable, and means controlled over said trunk switch for thereafter rendering said connector switch selectable. 80
28. In a telephone exchange system, a plurality of connector switches, a trunk switch, means for selecting an idle connector switch independent of said trunk switch, means controlled in the selection of said connector switch for causing said trunk switch to effect connection therewith, means for causing the operation of said connector switch, means controlled in the operation of the connector switch to render said connector switch unselectable, means controlled through said trunk switch for again rendering said connector switch selectable. 90
29. In a telephone exchange system, the combination of a link circuit having a trunk switch permanently associated therewith, a plurality of connector switches, an operator's position, means controlled from said position for automatically selecting an idle one of said connector switches independent of said trunk switch, means thereafter controlled from said position for causing the operation of said connector switch, and means also controlled from said position through said link circuit to operate said trunk switch to effect connection with the selected connector switch, and means controlled in the operation of the connector switch for rendering said connector switch unselectable, and means controlled through said trunk switch for again rendering said connector switch selectable. 100
30. In a telephone exchange system, the combination of a plurality of connector switches, a trunk switch adapted to be con- 110

nnected with any one of said connector switches, manually controlled means for pre-selecting an idle one of said connector switches independent of said trunk switch, 5 and means for associating said trunk switch with the preselected connector switch.

31. In a telephone exchange system, the combination of a connector switch, a trunk switch for effecting connection with said 10 connector switch, means independent of said trunk switch for selecting said connector

switch, means for operating said connector switch when selected to render it unselectable, and means controlled by said trunk switch to again render said connector switch 15 selectable.

In testimony whereof I affix my signature in the presence of two witnesses.

JOSEPH L. WRIGHT.
